SYSTEM OF MINING

Samuel M. Cassidy and George M. Rigg,
Uniontown, Pa.

Application March 4, 1942, Serial No. 433,270

4 Claims. (Cl. 262—1)

Our invention relates to the art of mining and particularly to improvements in the system of mining coal known as the room and pillar system. The purpose of our invention is to increase the operating efficiency of mining machinery now being used in coal mines. However, our invention may be used to great advantage in coal mines not employing mining machinery extensively.

In the mining of coal, a cut or kerf is first made along a working face of the body of coal to be removed. This cut is made at the top, bottom, or sides of the working face and is done by a large machine known as a cutter operated by two men. The cutter is then removed and a separate crew of workers drill holes above or below the kerf into which explosive is placed to "shoot down" the coal. After the coal is shot down another crew of workers load the coal into cars. In modern mining methods this loading is usually done by large mechanical loaders, scrapers, conveyors, or shaking conveyors. Following the loading and removal of the coal, separate additional crews erect timber to support the roof of the room which was formerly supported by the coal and lay track for the cutting and loading machines and the cars which are used for hauling the coal out of the mine. If conveyors are used, the crews erect extensions on to the conveyors.

As stated above, these operations, particularly the cutting and loading of the coal, are done by large machines which are difficult to move and which represent a considerable capital investment. In systems of mining which have heretofore been used, the various working faces in a mine are widely separated so that a large amount of time is required to remove the machinery from one working face to another. As a result the machinery is idle, so far as the actual mining of coal is concerned, for considerable periods of time. Likewise, the crews which operate the machines are not continuously employed in the mining of coal.

We have invented a system of mining by which these disadvantages have been overcome. In our system of mining, a large number of working faces are concentrated within a relatively small space so that the coal mining machinery can be quickly moved from one working face to another. The machines are thus used for the actual mining of coal during a large proportion of the time they are in the mine. The crews in charge of the machines are likewise continuously employed in actual mining operations.

In the accompanying drawing we have shown a diagrammatic plan view of a body of coal in which a system of mining embodying our invention is employed. As shown in the drawing, our system comprises the driving of several entries 2 to form main headings. In the drawing we have shown the main headings as having five entries although any number of entries may be used so long as there is proper provision for haulage of the coal and ventilation. The entries 2 are connected with each other by cross entries 3 which are cut when the entries 2 are being driven into the body of the coal to be mined. The cross entries 3 are closed by stoppings 4 to prevent short-circuiting of the flow of air through the entries for ventilation purposes. From the main headings, room entries 5 are cut into a panel 1 of the body of coal for the full depth thereof. As shown, the room entries are cut intermediate the sides of the panel. A sufficient number of room entries should be driven so that there is adequate provision for haulage and ventilation. As was done with the main headings, we have illustrated five room entries.

In the drawing we have shown a diagrammatic plan view of a mine after operations in accordance with our system have proceeded to a certain extent. The entries 5 have been completed and rooms or cross entries 6 have been cut to form a row of pillars 7 extending in a line across the entries and of such length as is determined by the requirements of efficient ventilation and removal of the coal. The row of pillars extends the full depth of the rooms on each side of the room entries.

The row of pillars 7 is not mined but is left standing for reasons which will hereafter be stated.

As shown in the drawing, rooms 6 are turned off of the room entries 5 on both sides thereof at an angle less than 90°. The resulting pillars are then mined, beginning with the row next to row 7. As the robbing of the pillars proceeds, the mine roof, being unsupported, caves in as shown by the stippled area in the drawing.

The rows of pillars which have been formed are mined in accordance with a system which will now be described. The drawing shows the pillars in rows 8, 9 and 10 being robbed or removed by mining on the retreat. Any method of mining suitable for removing pillars may be used. In the drawing we have shown each pillar as having a lift 11 in which the cutting, shooting down and loading takes place at working faces in each lift. The rows 8, 9 and 10 thus

afford a plurality of working places extending across the room entries for substantially the full width of the panel on a line of robbing substantially normal to said entries 5. These working places are all concentrated within a relatively small space so that cutters, loaders and other mining machinery can be easily and quickly moved from one to another. The line of robbing on the retreat is thereafter maintained substantially normal to the room entries, and thus always intersects a plurality of rows of pillars. In other words, the line of robbing is inclined from the room entries toward the headings with respect to the rows of pillars.

While mining proceeds at the line of robbing, additional rooms are cut by extending the rooms 6 as indicated in dotted lines at the points 12 in the drawing. It will be noted that these additional rooms will form additional rows of pillars generally parallel to the rows 9 and 10. The additional rooms are cut at such a rate that as pillars are removed at the line of robbing, additional pillars will be available for mining. Thus, in the drawing, the row 10 is shown as being ready for mining and is actually started before row 9 is removed. While the last pillars in row 9 are being mined, the pillars in row 10 assist in the support of the roof so that less timber is required. The rooms are also cut at such a rate that only a few rows of pillars are being formed in back of the line of robbing. This leaves a solid block of coal in back of the line which assists in the support of the roof. The panel 1 is thus mined in accordance with our system until the coal has been removed back to the barrier pillar 13 which is left to support the entries 2 forming the main headings.

The first row of pillars 7 formed at the end of the room entries is allowed to stand so as to form a bleeder entry 14 to draw off gases collecting in the caved in roof or "gob" 8. Also, a row of pillars at one side of the panel are allowed to remain as mining proceeds so as to form a second bleeder entry running parallel to the room entries. In the drawing we have shown a row of pillars 15 which will form a bleeder entry 16 similar to the bleeder entry 17 which was formed on the opposite side of the room entries 5 by the mining of the panel of coal adjacent to the panel 1. The purpose of the bleeder entries 16 and 17 is to assist in removing gases formed in the "gob" 8. The entries 5 are connected by short cross entries 18 cut during the driving of the room entries. The cross entries 18 as well as the rooms 6 all have the usual stoppings or doors which are designed to prevent the short-circuiting of air which flows through the mine for the purpose of ventilation. The flow of air through our system of mining is indicated by arrows in the drawing.

While the panel 1 is being mined as described above, another set of room entries 19 can be driven into a panel of coal adjacent to the panel 1. These entries can be cut at such a rate that they will have reached the full depth of the panel of coal in which they are driven at the time the mining has been completed back to the barrier 13 in the panel 1. This second panel will then be ready for the room and pillar work which has been described above.

By having a plurality of working faces concentrated in a relatively small area, we greatly reduce the time which has heretofore been lost in moving the coal mining machinery from one working face to the other. Moreover, the ma-

chinery, the crews, the track and wiring system used for extracting the pillars are the same as used for cutting the rooms back of the pillar line. The same crews and equipment do both the extracting and development work. The tonnage rate is therefore greatly increased.

While our method of mining greatly reduces the time lost in moving machinery from one working position to another, this is only one of the many advantages arising from its use. Thus a very important advantage arises from the fact that as soon as the room entries and first cross-entries or rooms are completed, robbing of the pillars can be started along the full width of the panel. The full length remains available until the entire panel has been completed. In "room and pillar" methods of mining heretofore used only one or two places are started at first. The number of places is gradually increased the line of robbing being at a substantial angle to the advance entries, but it has required a period of weeks or months before the full panel width is being robbed. Likewise the number of places has decreased as the mining of a section neared completion.

Another advantage of our system resides in the fact that the roof is supported by rows of pillars close to the robbing line and by a solid block of coal behind these pillars. The danger of the roof collapsing is thereby decreased.

The development work or opening of the room entries, is kept at a minimum. Large blocks of coal are left which is a great advantage in pillar work. The development work is concentrated so that high tonnage rates are obtained while it proceeds as well as on the subsequent room and pillar operations.

The fact that the working faces are all connected to one central entry, greatly assists in the changing of mine cars behind the loading machine. Likewise, it is easier for the "swing" or "relay" motor to pick up empty and loaded cars where they are left.

Our system of mining requires less rock dusting and less time to do the actual rock dusting needed than in mining systems heretofore used. Since the working faces are concentrated in a smaller area, the amounts of wiring for electric power, pipe lines for drainage, track installation and maintenance, and timbering necessary to carry on the mining operations are all materially reduced. Our system makes possible a simpler system of ventilation, requiring fewer doors for controlling the circulation of air and gases through the mine. It also facilitates supervision and thereby promotes increased safety.

Because of these many advantages, our system of mining is not limited to coal mines using mechanical cutters, loaders, etc., but may be profitably used in mines using any mining method such as; hand mining, hand or mechanical methods using track, rubber tired equipment, or scrapers and conveyors instead of track.

While we have described a present preferred embodiment of our invention, it is to be distinctly understood that it may be otherwise variously embodied and practiced within the scope of the following claims:

We claim:

1. In a method of mining a body of coal, the steps comprising driving a set of headings into the body, turning a set of room entries laterally from the headings into an intermediate portion of a panel on one side of the headings and advancing said entries through the panel, turning rooms

off of both sides of the entries at the end thereof remote from the headings at angles less than 90° thereby leaving rows of pillars extending from both sides of the entries at the end of the panel remote from the headings, similarly turning additional rooms off of the entries leaving rows of pillars substantially parallel to the first-mentioned row but nearer the headings than the latter, robbing pillars on one side of the entries substantially along a line passing through pillars in a plurality of said rows, simultaneously robbing pillars on the other side of the entry along a line passing through a plurality of rows of pillars, and maintaining the lines of robbing substantially normal to said entries.

2. In a method of mining coal, the steps including driving a set of headings through a body of coal to be mined, turning a set of room entries off of said headings substantially centrally of the panel lying on one side of said headings, driving said entries through substantially the full depth of the panel, turning rooms off of both sides of said entries at angles of substantially less than 90° to said entries, adjacent the end of the panel remote from the headings, thereby leaving spaced rows of pillars extending on both sides of said entries at said angles thereto, robbing said pillars in retreat across the entire width of the panel simultaneously, commencing at the end of the panel remote from said headings, by establishing working places simultaneously in pillars lying in a plurality of adjacent rows, and maintaining the line of robbing substantially normal to said entries.

3. In a method of mining coal, the steps including driving a set of headings through a body of coal to be mined, turning a set of room entries off

of said headings substantially centrally of the panel lying on one side of said headings, driving said entries through substantially the full depth of the panel, turning rooms off of both sides of said entries at angles of substantially less than 90° to said entries, adjacent the end of the panel remote from the headings, thereby leaving spaced rows of pillars extending on both sides of said entries at said angles thereto, robbing said pillars in retreat across the entire width of the panel simultaneously, commencing at the end of the panel remote from said headings, by establishing working places simultaneously in pillars lying in a plurality of adjacent rows, and maintaining the line of robbing substantially normal to the entries.

4. In a method of mining coal, the steps including driving a set of headings through a body of coal to be mined, turning a set of room entries off of said headings intermediate the sides of a panel lying on one side of said headings, driving said entries through substantially the full depth of the panel, turning rooms off of both sides of said entries at angles of substantially less than 90° to said entries, adjacent the end of the panel remote from the headings, thereby leaving spaced rows of pillars extending on both sides of said entries at said angles thereto, robbing said pillars in retreat across the entire width of the panel simultaneously, commencing at the end of the panel remote from said headings, by establishing working places simultaneously in pillars lying in a plurality of adjacent rows, and maintaining the line of robbing substantially normal to said entries.
